BOTTOM FILLER FOR SHOES

Henry G. Lumbard, Auburn, Maine

Application December 7, 1943, Serial No. 513,227

2 Claims. (Cl. 36—30)

This invention relates to bottom fillers for the forepart cavity of shoes and consists in a novel shoe bottom structure possessing advantages which have been long sought by the industry.

For many years the shoemaking industry has contended against two incompatible requirements in the endeavor to produce a perfect shoe bottom. In the first place the forepart, which is repeatedly and severely flexed in every step taken by the wearer, must be highly flexible if the shoe is to be worn with comfort. In the second place the bottom must be thick enough and have enough strength and body to protect the foot of the wearer from the discomfort of feeling every under-foot roughness. I have discovered a satisfactory solution for this old and difficult problem by making a new combination from shoemaking elements that have been heretofore available but never before combined as I now propose to combine them and never before used to accomplish the highly desirable results achieved by my invention.

Plastic fillers have been used for many years, and while these are satisfactory from a standpoint of flexibility, they tend to become deformed and displaced in the shoe bottom by a process of slow flow so that the insole does not remain flat under the foot of the wearer but develops objectionable hollows and cavities. On the other hand, a multitude of different fillers of solid sheet material have been used of every conceivable composition and in a great many different physical shapes, but all of these sheet fillers have tended to stiffen the shoe bottom by the well known plywood effect and this has been the case even though the material of the sheet filler has been flexible itself and even though perforated or transversely grooved.

I have discovered, however, that all the objections above discussed may be avoided by preparing sole filler blanks from a sheet of firm insole stock by transversely and discontinuously slitting the sheet and expanding it as a whole so as to cause separation of the opposed edges of each individual slit. Having prepared the sheet stock in this manner, the filler blanks are cut to size and secured to the outer face of the insole within the overlasted margin of the upper.

In preparing the filler of my invention we start with a firm solid piece of insole material. It is then slashed in the manner explained and in or subsequent to the slashing operation the material is expanded. The usual procedure is to over-expand the material and then permit it to relax to some extent but not to go back to its original position but in any case to leave the opposed edges of each individual slash spaced apart.

The filler is then inserted in the shoe in this expanded condition and will accordingly bend without resistance and in no way impair the flexibility of the insole with which it is associated.

5 The filler of my invention can be used in any type of shoe that carries a filler and can be designed to provide the same thickness of material as the thickness of the overlasted margin of the upper or of the rib in a welt shoe and so prevent the insole from caving in when worn. The filler holds the insole up to the level of the sides of the shoe when worn regardless of its type of manufacture. The material of the filler is selected for its depression-resisting qualities, that is to say, 10 it should be of sufficiently firm texture to eliminate any possibility of flow under conditions of heat and pressure in wear or of matting down as might occur with a felted structure. One suitable material is available on the market under 15 the trade name of "Darex" and comprises a porous paper stock impregnated with a rubber compound. Any other tough fibrous sheet material may be used in the construction of the filler of my invention. In my prior Patent No. 2,181,787 20 I have disclosed a flexible insole made from sheet stock which is suitable also to be utilized in preparing fillers in accordance with the present invention.

25 The features and characteristics of my invention will be best understood and appreciated from the following description of a preferred embodiment thereof selected for purposes of illustration and shown in the accompanying drawing in which,

30 Fig. 1 is a view in perspective showing a sheet of filler material with a single filler blank cut therefrom;

35 Fig. 2 is a view in perspective of a filler blank;

40 Fig. 3 is a fragmentary view in perspective and on an enlarged scale illustrating the process of slashing and expanding the sheet material;

45 Fig. 4 is a view in perspective showing the filler of my invention in position in the bottom of a welt shoe; and

50 Fig. 5 is a fragmentary view of the forepart of a cement lasted shoe embodying my invention.

In preparing the filler of my invention a sheet 10 of artificial leather, fibreboard, "Darex" or the like is selected of the thickness required in the filler. The sheet is then slashed by rows of closely adjacent short slashes 11 extending entirely through the material and from side to side, the individual slashes intersecting the edges of the sheet wherever they happen to fall. The slashes 11 are accurately aligned in their respective rows and are staggered in adjacent rows. The ma-

terial of the sheet 10 is expanded in such a manner as to space the opposed edges of each individual slash or slit from each other to such an extent that they do not make contact when the sheet or filler is flexed even to an extent greater than that at which it is flexed in ordinary wear. The step of expanding the material may be effected after the slashing operation or it may be effected simultaneously with the slashing operation as suggested in Fig. 3. In this instance 10 slashing is effected by a flat blade 13 having a cutting edge beveled at an angle sufficiently obtuse to stretch the stock substantially where it remains unsevered between the ends of adjacent slashes 11.

Sole filler blanks 12 may now be cut from the slashed and expanded sheet 10 by dies or by means of a pattern giving the filler the exact or approximate size and outline of the cavity in the forepart of the shoe wherein the filler is to be used. A filler blank 12 as removed from the sheet 10 is shown in Fig. 2.

In Fig. 4 is shown a welt shoe having an insole 14, an upper 15 having its margin 16 overlasted about the heel seat portion of the insole and secured to a welt 17, and an insole rib which extends throughout the shank and forepart of the shoe. In this instance the insole rib defines the forepart cavity which is to be occupied by the filler 12. After the welt 17 has been sewn and trimmed the filler blank 12 is fastened in place upon the outer face of the insole 14 and lies with its outer face substantially flush with the surface of the welt 17 thus completely filling the forepart cavity with solid material but without in any way impairing the flexibility of the insole with which it is associated. In Fig. 4 the upper is shown as lasted upon a last 20 and the shoe therein shown is completed by having an outsole 18 sewn to the welt.

In Fig. 5 I have shown the application of the

filler of my invention to a cement lasted shoe having an upper 25 with its margin overlasted upon the outer face of an insole 24 made in accordance with the process of my Patent No. 2,181,787; that is to say, the insole 24 is made flexible by the same treatment that is used to provide the flexible filler 12. In this instance the thickness of the filler is determined by the thickness of the overlasted margin 26 of the upper 25 and may be somewhat less than the thickness of a filler required in a welt shoe.

Having thus disclosed my invention and described in detail an illustrative embodiment thereof, I claim as new and desire to secure by Letters Patent:

1. In a flexible shoe having an insole with an upper overlasted upon its margin and an outsole, the combination with the insole, of a flexible filler comprising a blank of insole stock fitted within the overlasted margin of the upper upon the outer face of the insole and transversely slashed in adjacent parallel rows of short, aligned, through-and-through slashes extending from edge to edge of the filler and intersecting both edges thereof, the material of the filler being expanded and the opposed edges of each individual slash thereby separated sufficiently to remain out of contact when the shoe bottom is flexed in wear.
2. In a flexible shoe the combination of an insole transversely slashed in discontinuous rows of individual slashes, in combination with a filler of firm insole material approximately filling the forepart cavity of the shoe bottom and lying upon the outer face of the slashed insole, said filler itself being transversely slashed in parallel rows of short through-and-through slashes extending from edge to edge and having its material expanded whereby the opposed edges of each individual slash are separated and remain out of contact when the shoe bottom is flexed in wear.

HENRY G. LJUMBARD.
